UNITED STATES PATENT OFFICE.

JEROME I. WOHL, OF CHICAGO, ILLINOIS.

DESIGN FOR A COOLER.

Application filed July 20, 1928. Serial No. 27,538. Term of patent 3½ years.

To all whom it may concern:

Be it known that I, JEROME I. WOHL, a citizen of the United States, residing at Chicago, in the county of Cook and State of Illinois, have invented a new, original, and ornamental Design for a Cooler, of which the following is a specification, reference being had to the accompanying drawing, forming part thereof.

The figure is a perspective view of the cooler showing my new design.

I claim:

The ornamental design for a cooler substantially as shown.

JEROME I. WOHL.
